UNITED STATES PATENT OFFICE.

JOHN P. HILLMAN, OF KANSAS CITY, MISSOURI.

GAS-GENERATING OIL BURNER.

Application filed April 1, 1922. Serial No. 548,848.

To all whom it may concern:

Be it known that I, JOHN P. HILLMAN, a citizen of the United States, residing at Kansas City, in the county of Jackson and 5 State of Missouri, have invented a new and useful Gas-Generating Oil Burner, of which the following is a specification:

My invention relates to gas generating oil burners, and particularly to a device of this 10 character which is used in connection with furnaces and stoves.

The object of the invention is to provide a simple and efficient gas generating oil burner having facility for converting fuel 15 oil into a vapor gas which is combustible and then to burn the gas generated to provide an intense flame to simultaneously heat the gas generator to continue the generating process and to radiate heat to keep the furnace or stove hot.

Another object of the invention is to provide the burner with facility for automatically closing the mouth of the oil feed inlet to the generator to prevent back pressure in 25 feed line.

A further object of the invention is to surround the generator with a cold air flue to direct cold air to the burning gas to effect maximum combustion of the gas.

Another object is to provide a condensing manifold to deliver gas from the generator to the gas holder and to effect condensation of the vapor gas so that the gas delivered to the gas holder shall be substantially dry.

I attain these objects and other advantages by means of the combination of parts and structure illustrated in the accompanying drawing in which—Figure 1, is a sectional view of a gas generating oil burner constructed in accordance with my invention, and, Figure 2, is a top plan view of the complete device, and showing the same in operative position on the fire grate of a furnace.

Similar numerals of reference refer to corresponding parts throughout the several views.

Referring to the drawings—the numeral 1, designates a furnace fire grate provided with the usual grate bars 2. The burner comprises an inverted U-shaped air flue 3, which is adapted for standing vertically of the furnace and to extend down through the grate. In the upper side of the horizontal portion 55 of the air flue is a hole 4, and directly therebelow, in the lower side of the flue is an

opening 5, for the egress of the air flowing into the flue to the fire. Over the air flue is a gas holder member 6, having an outlet 7, through a boss 8, and in the outlet is suitably 60 mounted a nozzle 9, which is adapted for its projection into the air flue, through the hole 4, thereby, providing communication between the gas holder and the flue. The upper end of the nozzle 9, is fashioned to seat 65 a valve 10, on the lower end of a stem 11, which is provided externally with screw threads which engage internal screw threads in a boss 12, which is integral with the upper side of the gas holder, the upper portion of the stem is formed at right angles to the stem to form a handle 13 for manipulating the valve 10. On the side portions of the air flue, inwardly of the ends thereof, is mounted a circular gas generating retort 14, 70 provided with a convexed head 15, the generator or retort being stationed directly below the opening 5, in the air flue. A condensing manifold 16, is connected between the gas holder 6, and the retort 14, and the 75 manifold is arranged to pass through one side of the flue and to be partially housed thereby. The lower side of the retort is flat, so that the retort may be placed upon the grate bars of the furnace and, thereby, assist 80 to hold the air flue vertical.

On the inner side of the lower side of the retort is an upwardly extending boss 17, and on the outer side of the lower side of the retort is a boss 18, through which bosses is 85 a hole forming an inlet 19, to the retort, for feeding fuel oil therethrough, the space about the inlet in the retort being a basin to catch oil and condensed vapor returning from the manifold. In the upper end of the 90 inlet 19, is movably mounted a pin 20, having a flat head 21, which is adapted for seating upon the inner end of the inlet to normally close the mouth of the inlet, the nail being prevented from leaving the inlet by 95 the close proximity of its head to the upper side of the retort. In the boss 18, is screwed the end of a pipe 22, which is connected with a fuel oil supply, not shown, and on the pipe is mounted a collar 23, for supporting 100 thereon a pan 24, which is extensive enough to catch dripping oil and waste from the burner, the pan being provided with a stopcock 25, to draw off the contents of the pan. Encircling the retort is a drum 26, which 105 drum is spaced apart from the retort a suitable distance to form of the intervening

space a flue 27, for the passage of cold air from below the grate to the burning gas, the drum being held in place by angle irons 28, which are attached to the drum and 5 fastened on the sides of the air flue 3.

When the parts are operatively assembled, as shown in Figure 1, the device is placed in the furnace, upon the fire grate, suitable openings in the grate being made to permit 10 the end portions of the air flue 3, to extend therethrough and project a little distance into the ash pit, the retort 14, being thus brought to bear on the upper side of the grate. The feed pipe 22, is then screwed 15 into the retort, the pan 24, being mounted on the pipe, the latter then being connected with a supply of fuel oil, not shown. After the burner device is in place in the furnace, the upper side of the grate is covered, preferably, with asbestos 29, to prevent air flowing 20 into the furnace excepting through the air flues 3 and 27. The fuel oil is then permitted to flow through the feed line 22, through the inlet 19, into the retort, the 25 pressure of the oil being sufficient to press up the pin 20, until the head thereof is against the upper side of the retort and thereby keeping the mouth of the inlet open. From the retort the oil rises through 30 the manifold 16, into the gas holder 6, the oil falling through the nozzle 9, and through the opening 5, in the air flue 3, upon the head of the retort, the valve 10, being opened to permit the oil to escape 35 from the gas holder. The oil is then lighted at the top of the retort, whereupon the oil will burn and effect a heating of all the parts of the device. When the oil is burning the cold air from below the grate flows into 40 the furnace through both the air flues 3 and 27, thus causing the fire to burn with great heat and effect a heating of the parts of the device. The heated parts generate gas from the oil until the retort is hot enough to generate 45 gas from the oil supplied to it and, thereafter, the retort supplies all the gas required to keep the fire alive. After the retort becomes properly heated to generate gas the oil fed to the retort is converted into 50 a combustible gas or vapor which is more or less charged with moisture, the expansion of the gas induces a pressure to force the gas to flow through the manifold 16, into the gas holder 6, and from thence through 55 the nozzle 9, into the air flue 3, where it mixes with the air flowing through the flue, thereafter passing through the opening 5, to be consumed by the fire started as hereinabove described, the force of the flow of gas 60 sending the gas down to and against the convexed top of the retort from whence it is spread outwardly of the retort to and against the sides of the furnace. As the burning gas is spreading from the top of the 65 retort, cold air from the ash pit of the fur-

nace rushes into the fire through the flue 27, thus supplying additional oxygen to the fire and effecting thereby substantially complete combustion of the gases and obtaining an incandescent flame of great intensity. The 70 gas in passing through the manifold from the retort to the gas holder, strikes the cold portion of the manifold, which is housed in the air flue 3, and thereby the gas parts with its moisture, in the well understood manner, 75 the condensed moisture gravitates back to the retort in liquid form, to be again vaporized. This provision causes delivery of dry gas to the gas holder.

The nozzle 9, being removably secured in 80 the gas holder outlet, the nozzle may be taken out and cleaned when necessary. The taper of the valve 10, is designed to provide a point which shall enter into the nozzle and thereby keep the same free of dirt. 85 The taper also has relation to the proper feed of gas by manipulating the valve to regulate the flow of gas, the screw threads on the stem of the valve permitting of very close adjustments of the valve with its seat. 90

It is known that gas generating oil burners frequently set up pulsations in the gas feed and create back pressure in the oil feed line. To prevent back pressure in the oil feed line, I have provided the pin 20, which is mounted in the inlet 19, so that if there is back pressure the pin will drop into the outlet and bring the under side of its head to bear on the end of the outlet, thereby, effectually preventing back pressure in the 100 oil feed line.

Having described my invention what I claim is—

1. In a gas generating oil burner, the combination of an inverted U-shaped air flue 105 having an outlet opening intermediate of the horizontal portion thereof, a gas generating retort stationed below the outlet in said flue and having an inlet projecting inwardly of the retort, a gas holder stationed 110 above said air flue and vertically aligned with the outlet opening therein, a valve mounted on said gas holder and operable to regulate the flow of gas from the holder to said air flue, and a manifold connected 115 between said retort and said gas holder and partially housed by said air flue.

2. In a gas generating oil burner, the combination of an inverted U-shaped air flue having an outlet opening intermediate 120 of the horizontal portion thereof, a gas generating retort stationed below the outlet in said flue and having an outlet projecting vertically inward of the retort, a stopper movably mounted in the inlet in said retort to normally close the mouth of the inlet, a gas holder stationed above said air flue and having an outlet projecting into the flue and vertically aligned with the outlet opening 125 therein, and a manifold connected between 130

said retort and said gas holder and partially housed by said air flue.

3. In a gas generating oil burner, the combination of an inverted U-shaped air flue having an outlet opening intermediate of its horizontal portion, a gas generating retort stationed below the outlet in said air flue and having an inlet projecting vertically inward of the retort, the head portion 10 of said retort being convexed to form a spreader, a stopper movably mounted in the inlet in said retort to normally close the mouth of the inlet, a gas holder stationed above said air flue and having an outlet 15 projecting into the flue and vertically aligned with the outlet opening therein, and a manifold connected between said retort and said gas holder and partially housed by said air flue.
- 20 4. In a gas generating oil burner, the combination of an inverted U-shaped air flue having an outlet opening intermediate

of its horizontal portion, a gas generating retort stationed below the outlet in said air flue and having an inlet projecting vertically inward of the retort, the head portion 25 of said retort being convexed to form a spreader, a stopper movably mounted in the inlet in said retort to normally close the mouth of the inlet, a gas holder stationed 30 above said air flue and having an outlet projecting into the flue and vertically aligned with the outlet opening therein, a manifold connected between said retort and said gas holder and partially housed by said 35 air flue, and a tubular member surrounding the sides of said retort and spaced therefrom to form with the sides of the retort a flue.

Kansas City, Missouri, March 29th, 1922.
